UNITED STATES PATENT OFFICE.

CLARANCE A. WILLIAMS, OF MERRILLVILLE, CALIFORNIA.

WRENCH.

1,160,680.

Specification of Letters Patent. Patented Nov. 16, 1915.

Application filed June 8, 1915. Serial No. 32,890.

To all whom it may concern:

Be it known that I, CLARANCE A. WILLIAMS, a citizen of the United States, residing at Merrillville, in the county of Las-
5 sen and State of California, have invented a new and useful Wrench; and I do hereby declare the following to be a full, clear, and exact description of the invention, such as will enable others skilled in the art to which
10 it appertains to make and use the same.

This invention relates to an improved wrench, and an object of the invention is to provide a wrench which is simple, efficient and practical in construction, and the shank
15 handles of the jaws are so made, as to enable the operator to secure a long leverage, upon that which is to be turned, and without allowing the jaws to become loose or separated.

20 Another object of the invention is to provide an improved wrench, so constructed, as to enable the operator to secure slight adjustment of the jaws, and at the same time to permit substantially a three-cornered
25 grapple and bracing effect in wrenching that which is to be turned.

One of the features of the invention is the provision of two jaws, one of which is longitudinally channelled, for the reception of
30 the other jaw, the sides of the channelled jaw having angularly disposed registering slots, through which the guide pin which is rectangular in cross section extends, the guide pin being carried by the jaw which is adjustable in the channel. The gripping faces
35 of the jaws extend at an obtuse angle to the length of the shank handles, and at right angles to the slots, thereby permitting the jaws to be inserted in inconvenient places,
40 and yet permit a long leverage and considerable movement of the handle of the wrench.

This particular type of wrench is more especially adapted for laying railway tracks and the like, in view of the fact that the
45 jaws are enabled to reach up under the nuts in applying fish plates so that the wrench may be given a half turn.

In practical fields the details of construction may necessitate alterations, falling
50 within the scope of what is claimed.

The invention comprises further features and combination of parts, as hereinafter set forth, shown in the drawings and claimed.

In the drawings: Figure 1 is a view in
55 side elevation of the wrench, showing the same in engagement with the nuts on the

side of a rail, whereby substantially a full half turn may be imparted to the nut. Fig. 2 is a perspective view. Fig. 3 is a sectional view longitudinally, showing parts in
60 elevation.

Referring more especially to the drawings, 1 designates the jaws of the wrench. The jaw 1 is enlarged and substantially diamond shaped and provided with the lug
65 3, which constitutes the gripping jaw proper. This diamond-shaped enlarged portion of the jaw 1 is longitudinally channelled as shown at 4, which channel 4 extends entirely through the jaw 1 as shown at 7.
70 The opposing sides of the jaw 1, between which sides the channel is formed, are provided with angularly extending registering slots 8. The jaw 2 is provided with an enlargement 9, which is adjustable in the
75 channel, and the tongue portion 10 of this enlargement 9 extends through that portion of the channel which extends entirely through the jaw 1. Removably fixed in a square aperture of said tongue is a correspondingly constructed pin 11, the opposite
80 ends of which engage the registering slots 8, thereby guiding the jaw 1 during its various adjustments.

In practice the ends of the rectangular
85 pin 11 have sufficient play in the slots 8, to permit the pin to slide, and this play is sufficient to permit the jaw member having the tongue to rock just enough to permit the tooth 20 of the shank 22 to move out of engagement with the ratchet teeth 19, so that the jaw members may be adjusted. Forming an integral part of the jaw 2 is a lug
90 14, which constitutes the other gripping jaw proper for co-operation with the jaw 3. 95 The shoulders 15 of the jaw proper 14 engage the edge portion 16 of the jaw 1. The shank handle 17 at its extremity is constructed with a socket housing 18, and its inner wall 18 is provided with ratchet teeth
95 19, to be engaged by the tooth 20 at the extremity 21 of the handle shank 22 of the jaw 2, so as to prevent movement of the jaw 2 in the direction of the socket housing. A suitable spring 23 is bent or constructed as shown at 24, so as to engage the transverse pins or lugs 25 of the socket housing, for holding the spring in position. The free portion 26 of this spring engages the edge 27 of the shank handle of the jaw 2,
100 110 in order to hold the tooth 20 in engagement with any two of the teeth 19 of the socket

housing. The shank handle of the jaw 2 is provided with suitable serrations or milled surfaces 29 and 30, to constitute gripping surfaces, for adjusting the jaw 2.

5 To adjust the jaw 2 relative to the channel jaw member, the jaw member 2 is moved just a trifle, to permit the extremity of the tooth 20 to slide forwardly upon the inclined part of one of the teeth 19 sufficiently, 10 to permit the tooth 20 to be moved from engagement with the respective tooth of the teeth 19, and in moving the tooth 20 out of engagement with the teeth 19, the pin 11 rocks but a trifle in the slots 8. In practice 15 the teeth 19 will be constructed considerably smaller and in greater numbers, for the showing of the teeth 19 in the drawing is exaggerated for the mere purpose of illustration, and in case the play of the pin 11 20 in the slot 8 is not sufficient, the extreme portion of the shank 22 may be sprung sufficiently to permit the tooth 20 to be disengaged from the teeth 19.

The invention having been set forth, what 25 is claimed as new and useful is:—

1. A wrench comprising a pair of jaw members, one of them being provided with an enlargement and having a channel extending longitudinally thereof and entirely 30 through the jaw, said channel in cross section being elongated, the other jaw member having an enlargement of a shape transversely corresponding to the contour of the channel transversely and fitting the channel, 35 and having a tongue extending through that portion of the channel which extends through the first jaw, the opposite sides of the channel jaw member being provided with elongated registering slots extending 40 angularly and in a direction toward the shanks of the jaw members, means carried by the tongue and guided in said slots, said jaw members having opposing coöperating jaws proper extending at obtuse angles to the 45 jaw members and at right angles to the slots, one of the jaw members terminating in a shank handle having a socket housing, the other jaw member having a shank handle 50 engaging the socket housing, and means in the socket housing for holding the jaw members in adjusted positions.

2. A wrench comprising a pair of jaw members, one of them being provided with an enlargement and having a channel extending longitudinally thereof and entirely 55 through the jaw, said channel in cross section being elongated, the other jaw member having an enlargement of a shape transversely corresponding to the contour of the 60 channel transversely and fitting the chan-

nel, and having a tongue extending through that portion of the channel which extends through the first jaw, the opposite sides of the channel jaw member being provided with elongated registering slots extending 65 angularly and in a direction toward the shanks of the jaw members, a pin extending transversely of the tongue and being guided in said slots, said jaw members having opposing coöperating jaws proper extending at 70 obtuse angles with the jaw members and at right angles to the slots, said jaw members having shank handles, one of the shank handles having a socket housing provided with teeth upon one of its interior surfaces, 75 the other shank handle having a tooth at its extremity to engage any one of said teeth to prevent movement of the jaw member adjustable in the channel, and a spring fixed in the socket housing to hold said tooth in 80 engagement with said teeth.

3. A wrench comprising a pair of jaw members, one of which is provided with an enlargement having a channel extending angularly and entirely through the enlargement, said channel in cross section being elongated, the other jaw member having an enlargement of a shape corresponding to the contour of the channel transversely and fitting the channel, and having a tongue 90 extending through that portion of the channel which extends through the first jaw, the opposite sides of the channel jaw member being provided with elongated registering slots extending angularly in a direction toward the shanks of the jaw members and substantially corresponding to the disposition of the channel, a pin rectangular in cross section and carried by the tongue and guided in said slots, said jaw members having opposing coöperating jaws proper extending at obtuse angles to the jaw members and at right angles to the slot, the sides of the channel jaw member having guiding shoulders, the jaw member having the 95 tongue being provided with guiding shoulders adjacent the jaw proper to coöperate with the first guiding shoulders, the jaw members terminating in shank handles, one having a socket housing to receive the other 100 and provided with means for holding the 105 jaw members in adjusted positions.

In testimony whereof I have signed my name to this specification in the presence of two subscribing witnesses.

CLARANCE A. WILLIAMS.
